A. R. HAAG

WRINGER

Filed July 25, 1924

Inventor:
Albert R. Haag
By *Left & Tepper*
Attorneys.

UNITED STATES PATENT OFFICE.

ALBERT R. HAAG, OF PEORIA, ILLINOIS.

WRINGER.

Application filed July 25, 1924. Serial No. 728,078.

To all whom it may concern:

Be it known that ALBERT R. HAAG, a citizen of the United States of America, residing at Peoria, in the county of Peoria and State of Illinois, has invented certain new and useful Improvements in Wringers, of which the following is a specification.

My invention relates to wringers.

The invention has reference to "quick release mechanism" applied to a wringer for the purpose of protecting the user as well as protecting clothing being wrung through it.

The invention also includes a special relationing of a tension spring member for the upper wringer roll in connection with the framing whereby said spring member is constantly held in a degree of tension as distinguished from a complete release and substantial detachment as is common in most wringer structures under conditions of the operation of quick release mechanism.

The invention also includes a special relationing of a top framing member with the main frame whereby a hinged relation is established to the end that the top member may be free to move under conditions of the operation of the quick release device and in such movement carrying with it a roller tensioning spring thereby releasing the latter from pressure. Such hinged relationship as between the top member and the bottom of the frame also facilitates ready removal of the wringer release as well as convenient assembly.

The invention also includes the matter of relative arrangement and support as between a bar spring tensioning member, the top framing member and spacing members intervening between the spring and wringer roll to establish a maximum of screw pressure force applied to the spring member notwithstanding the degree of deflection of the spring bar under the flexing force thereby automatically limiting the tension force applied to the upper wringer roll.

The invention also includes detailed structural parts and combination of parts as hereinafter more particularly indicated.

50 Referring to the drawings:

Fig. 1 is a side elevation showing a support and wringer associated therewith, the latter embodying features of the invention.

Fig. 2 is a vertical sectional view of the same subject matter disclosed in Fig. 1.

Fig. 3 is an end view of the wringer viewed from the position shown by the arrow in Fig. 1.

Fig. 4 is an end view similar to that shown in Fig. 3 with parts broken away and with the top framing member swung laterally from the main frame.

In referring to the drawings special reference will not be made to driving or supporting mechanism for the wringer as such features constitute no part of the present invention.

Referring to the drawings a framing member is shown comprising end members 10 and bottom member 11. This frame may be fashioned in one piece or may be made up of sections as herein disclosed and sections may be connected in the manner illustrated in the drawings. This main framing member is designed to house and support the working mechanism of the wringer.

Referring to the working mechanism of the wringer 12 is a lower wringer roll, its spindles having support in trunnion blocks 13, said trunnion blocks being fashioned for open seating of the spindles as shown, said blocks being in turn supported within the clearance way between the flange members of end framing members 10 and may together with the wringer roll, be readily disposed or removed from the frame by simple vertical lift except that in case of the roll, it is required that it shall be slightly inclined to relieve it from its driving connection as shown at the right of Fig. 2. 14 is a top wringer roll, its spindles being supported in trunnion blocks 15, the latter being in turn supported in the clearance way between the flanges or end framing members 10 thereby adapting them for ready removal together with the wringer roll.

Special attention is called to a top frame or head member which in the present instance comprises a unit member 16 fashioned with interior clearance space as shown that of the ends of the framing member corresponding to the width of the clearance space between the flanges of end members 10, whereby trunnion blocks 15 may be projected upwardly therein. The head member 16 is hinged to the main frame as at 17 as shown in Fig. 3 there being a similar hinge connection at the opposite end of the frame thereby adapting the head member to be swung laterally in clearance of the top

of the main frame thereby accommodating the entry or removal at option of all of the operating mechanism that is supported in the main frame. The head member is adapted 5 to be optionally locked to the main frame through and by means of catch members 18 fixed to rocker rod 19, the latter in turn being journaled in lug members 20 on the head. To rocker member 19 is fixed striking arm 21 which may as herein shown be a mere extension of catch member 18. The locking means above noted co-operates with lug members 22 on the main framing whereby force applied to striking arm 21 will 10 serve to turn rod 19 to effect additional locking of the release with respect to the head member and the main frame.

Referring particularly to the manner of relating a tensioning device to the framing and to the upper wringer roll, 23 is a 20 bar spring fashioned with an intermediate seat as 24 to receive the thrust of a screw member 25 operatively supported in head member 16.

25 The bar 23 is adapted to extend substantially the length of head member 16, its outer ends being supported upon cross pin members 26 fixed to the head member.

Normally a minimum degree of tension is 30 adapted to be applied through screw 25 to this spring to hold it in contact with pin members 26 so that it is never in the position to become dislodged.

35 Trunnion blocks 15 supported in the main frame are supported only from the bearing relation between rolls 12 and 14 so that it will appear that tension applied to said blocks will effect pressure relation as between the two rolls. Blocks 15 are so portioned that they project upwardly beyond the main frame to a point substantially coincident to a line corresponding to the upper edges of supporting pins 26 whereby under normal conditions no tensioning action 40 will be imparted to roll 14. However, spring 23 having been properly flexed under the action of screw member 25 to develop resisting force, clothing passed between rolls 12 and 14 will effect an upward projection 45 of roll 14 against the resistance of bar spring 23 transmitted through block members 15 to said spring. It will be noted here that through the tensioning arrangement here described, a minimum of spring tension 50 of roll 14 against the rollers when the wringer is idle is secured, this being a very desirable result as it prevents the damaging of the wringer by a careless person who might otherwise apply an unwarranted degree of pressure if the stop pin members 26 were not applied.

60 While I have shown herein my preferred embodiment of structure including a housing of a tensioning member in a hinged head or top framing member and the pro-

70 vision of stop members for limiting tension action of the spring, I comprehend that modifications over the form herein exemplified may be had to obtain the results here sought and therefore I do not wish to confine myself to the detailed combination or form of embodiment herein exemplified.

What I claim is:

1. A wringer having in combination, a 75 main frame, a top frame member hinged to the main frame and swingable laterally thereof, a pair of compression rollers mounted in said main frame, vertically movable bearings for the upper of said rollers, means for applying tension to said upper roller, the said tension applying means including a spring bar mounted in the top frame member and having the ends thereof in line with the movable bearings of the upper roller, whereby upward movement of said bearings produced by separation of the rollers is resisted by said spring bar when the top frame member is in operative position, and means on the upper frame member for limiting the impinging action 80 of the spring bar upon the movable bearings when the compression rollers are in contact with each other.

2. A wringer having in combination, a 85 main frame, a top frame member hinged to the main frame and swingable laterally thereof, a pair of compression rollers mounted in said main frame, vertically movable bearings for the upper of said 90 rollers, and means for applying tension to said upper roller, the said tension applying means including a spring bar mounted in the top frame member and having the ends thereof in line with the movable bearings of the upper roller, whereby upward movement of said bearings produced by separation of the rollers is resisted by said spring bar when the top frame member is in operative position, means on the upper frame member for limiting the impinging action 95 of the spring bar upon the movable bearings when the compression rollers are in contact with each other, and means carried by the top frame member for placing the 100 spring bar under initial tension.

3. A wringer having in combination, a 105 main frame, a top frame member hinged to the main frame and swingable laterally thereof, a pair of compression rollers mounted in said main frame, vertically movable bearings for the upper of said 110 rollers, means for applying tension to said upper roller, said tension applying means including a spring bar mounted in the top frame member having the ends thereof in line with the movable bearings of the upper roller, whereby upward movement of said bearings produced by separation of the rollers is resisted by said spring bar when 115 the top frame member is in operative posi- 120

tion, and stop members on each end of the said upper frame member adapted to position the ends of said spring bar relative to the top face of the bearings of the upper 5 roller when the rollers are in contact with each other.

4. A wringer having in combination, a main frame, a lug on said main frame, a top frame member hinged to the main frame 10 and swingable laterally thereof, a pair of compression rollers mounted in said main frame, vertically movable bearings for the upper of said rollers, and means for applying tension to said upper roller, the said 15 tension applying means including a spring bar mounted in the top frame member and having the ends thereof in line with the movable bearings of the upper roller, whereby upward movement of said bearings 20 produced by separation of the rollers is resisted by said spring bar when the top frame member is in operative position, means on the upper frame member for limiting the impinging action of the spring 25 bar upon the movable bearings when the compression rollers are in contact with each other, means for interlocking said frame members, and means for releasing the interlocking means, said releasing means includ-

ing a striker arm adapted to engage the lug 30 on the main frame.

5. A wringer having in combination, a main frame, a top frame member hinged to the main frame and swingable laterally thereof, means for interlocking the said 35 frame members, means for releasing the interlocking means, said releasing means including a striker arm, a pair of compression rollers mounted in said main frame, vertically movable bearings for the upper of 40 said rollers, and means for applying tension to said upper roller including a spring bar mounted upon the top frame member, means on said top frame member for holding the ends of said spring bar in a plane parallel 45 to the top face of the movable bearings when the compression rollers are in contact with each other, the movable bearings being adapted to rise relative to the last mentioned means to increase the pressure of the spring arm upon the bearings 50 when the rollers are separated by the introduction of work therebetween, and adjustable means for applying an initial tension 55 to the spring bar.

In testimony whereof I affix my signature.

ALBERT R. HAAG.
